UNITED STATES PATENT OFFICE.

VERNON J. STRATTON, OF CLOVERDALE, CALIFORNIA.

FLY-SCREEN.

958,562.

Specification of Letters Patent. Patented May 17, 1910.

Application filed August 3, 1909. Serial No. 511,021.

To all whom it may concern:

Be it known that I, VERNON J. STRATTON, a citizen of the United States, residing at Cloverdale, in the county of Sonoma, State 5 of California, have invented certain new and useful Improvements in Fly-Screens; and I do hereby declare the following to be a full, clear, and exact description of the invention, such as will enable others skilled in the art 10 to which it appertains to make and use the same.

This invention relates to improvements in door and window screens and has for its object the production of a screen provided with 15 an opening through which flies and other winged insects may exit from a room without difficulty but will be prevented from returning to the room through the opening in the screen.

20 Another object is the provision of a construction wherein the two members comprising the screen may be tightened whenever sagging occurs.

With these and other objects in view as 25 will more fully hereinafter appear, the present invention consists in certain novel details of construction and arrangement of parts, hereinafter fully described, illustrated in the accompanying drawings and more particularly pointed out in the appended claim; it being understood that various changes in 30 the form, proportion, size and minor details of the device may be made without departing from the spirit or sacrificing any of the 35 advantages of the invention.

In the accompanying drawings forming part of the specification:—Figure 1 is a front elevation of the device. Fig. 2 is a longitudinal sectional view thereof taken on the line 40 2—2 of Fig. 1 and showing the relative positions of the screen members and brace rods. Fig. 3 is a similar view on the line 3—3 of Fig. 1 and showing the seats for the brace rods.

45 Similar numerals of reference are employed to designate corresponding parts throughout.

The screen frame consists of the usual side and end sills designated by the numerals 5 50 and 6, and the molding strips which are secured to one face of the side and end sills and serve to clamp the screen to the said side and end sills are designated by the numerals 7 and 8.

55 Two screen members are employed in carrying out the invention and are designated

in general by the numerals 9 and 10. The edges of these members are secured in the usual manner between the opposed faces of the sills and molding strips as clearly shown 60 in Figs. 2 and 3. The combined lengths of the members is somewhat greater than the length of the door or window frame to which they are applied and in order that their opposed ends will not bear one upon the other 65 and at the same time to provide an opening through which the insects may exit each member is, at a point adjacent its free end, bent outwardly and at an angle as shown at 11. 70

The members 9 and 10 may be of unequal lengths as shown in the drawings the lower member 10 being of considerably greater length than the upper member 9 so that the opening formed by the bending of the opposed ends of the members will be located adjacent the upper end of the door or window frame and the extremities of the members be out of danger from accidental bending or defacement. 75

80 As before stated, the bent portions 11 extend outwardly from the sills comprising the screen frame. These bent portions are parallel with each other and extend in a plane oblique to the vertical plane of the screen frame and the opening between their opposed inner faces will be sufficient to permit a fly to pass therethrough.

In order to prevent the opening becoming closed due to the sagging or stretching of 90 either member, and at the same time to brace the members, brace rods 13 and 14 are employed. Each of these members is preferably formed of a single piece of wire and has its body portion soldered or otherwise 95 fixedly secured to the outer face of one screen member and is located in the crotch formed by the bent end portion and body of the member.

100 By referring now to Fig. 3 it will be seen that the side molding strips 8 are, on their inner faces, provided with transverse recesses 15 as shown in Fig. 3. These recesses correspond in width to the diameter of the brace rods 13 and 14 and in length to 105 the width of the openings between the bent end portions 11, or substantially so. The opposite end portions of the brace rods 13 and 14 extend into the recesses 15 and in the normal positions of the parts, the brace rods 110 will bear on the opposite ends of the recesses. When, for any reason whatever, the

members 9 and 10 sag or stretch, this sagging or stretching may be taken up by moving the brace rods 13 and 14 toward each other and then securing the parts in place by 5 means of wire bands 17, which extend through the meshes of the screen member and around the brace rods.

With this construction it can be seen that the screen as a whole may be preserved 10 against derangement for a comparatively long time.

It can be readily seen with a device of this kind that flies or other insects walking on the inner faces of the members and arriving at the opening will naturally pass through the same and out of the room or building, but owing to the comparatively small space and absence of a place to light in front of the opening, the flies will positively be prevented from returning to the room or building.

It can be further seen that the device is comparatively simple in structure and inex-

pensive to manufacture, embodying few parts and these so arranged that the danger 25 of derangement will be reduced to a minimum.

What is claimed as new, is:—

A fly screen, comprising a frame having alined recesses in its sides, a pair of brace 30 rods having their opposite ends slidingly fitted in said recesses, screen members secured to the ends of the frame and having their free ends bent to loosely embrace said rods and extend outwardly therebeyond in parallel planes, and adjusting elements connecting said rods and operating to vary the space between said outwardly extending screen portions.

In testimony whereof, I affix my signature, in presence of two witnesses.

VERNON J. STRATTON.
